Primary Examiner — Michael A. Pratt

(57) **CLAIM**

The ornamental design for a beverage bottle, as shown and described.

DESCRIPTION

1. Beverage bottle
2. Beverage bottle
4. Beverage bottle
5. Beverage bottle
6. Beverage bottle
8. Beverage bottle
1. Beverage bottle
- 1.1 : Front
- 1.2 : Rear
- 1.3 : Left
- 1.4 : Right
- 1.5 : Bottom
- 1.6 : Top
- 1.7 : Rear Perspective
2. Beverage bottle
- 2.1 : Front
- 2.2 : Rear
- 2.3 : Left
- 2.4 : Right
- 2.5 : Bottom
- 2.6 : Top
- 2.7 : Rear Perspective
4. Beverage bottle
- 4.1 : Front
- 4.2 : Rear
- 4.3 : Left
- 4.4 : Right
- 4.5 : Bottom
- 4.6 : Top
- 4.7 : Rear Perspective
5. Beverage bottle

(Continued)

5.1 : Front
5.2 : Rear
5.3 : Left
5.4 : Right
5.5 : Bottom
5.6 : Top
5.7 : Rear Perspective
6. Beverage bottle
6.1 : Front
6.2 : Rear
6.3 : Left
6.4 : Right
6.5 : Bottom
6.6 : Top
6.7 : Rear Perspective
8. Beverage bottle
8.1 : Front
8.2 : Rear
8.3 : Left
8.4 : Right
8.5 : Bottom
8.6 : Top
8.7 : Rear Perspective
